CULTIVATING ATTACHMENT FOR PLOWS

David R. Jamerson, Dallas, Tex., assignor to
H. E. Vaughan, Dallas, Tex.

Application July 31, 1947, Serial No. 765,085

2 Claims. (Cl. 97—6)

1

This invention relates to agricultural implements and more specifically to attachments for turning plows and similar devices, the usefulness of said invention being manifest in the aid it renders in the eradication of useless and/or parasitic vegetation.

The principal object of this invention is to provide a revolving disintegrator for separating the soil from the vegetation, a novelty of its construction being its tapered design which adapts it to irregular terrain.

Another object of the invention is to provide a flexibility of movement for the various parts of the device in their mutual relationship.

Still another object of the invention is to provide means for attachment to the beam of a turning plow, said means for attachment permitting rigid angular relationship between the plow share and the revolving disintegrator.

With the foregoing objects as paramount, the invention has reference to certain features of construction and performance which will become increasingly apparent as the description proceeds, taken in connection with the accompanying drawing, wherein:

Figure 1 is a perspective view of the invention illustrating its position in relation to a turning plow, the latter being shown fragmentarily.

Figure 2 is a fragmentary perspective view of the invention, illustrating in greater detail the means for attaching it to the beam of a turning plow.

Figure 3 is a fragmentary rear elevational view of a modified form of the invention, illustrating the means provided to permit certain convolutions of the spiral to obtain lateral movement in relation to other convolutions, and showing a gradual reduction in the diameter of the spiral.

Figure 4 is a fragmentary sectional view of the spiral illustrating in greater detail the construction shown in Figure 3, and

Figure 5 is a rear elevational view of the plurality of rings or hoops, forming the disintegrator, illustrating a means for rigid axial support for the smaller end, and the lugs attached thereto as means for obtaining traction.

Continuing with a more detailed description of the drawing, and referring particularly to Figures 1 and 2, reference numeral 10 denotes the beam of a plow frame, having a plow share 11 attached thereto below an angular bend thereof. It is not intended herein to limit the adaptations of the invention to use in combination with or attachment to a turning plow, as the design and construction of the invention is such as to be of

2

great practical use in operation with other types of implements and/or machines.

Referring now to Figures 1 and 5, it will be noted that the disintegrating unit of the invention comprises a plurality of hoops or rings 12, maintained in spaced proximity by a series of laterally disposed straps 13. In this design the outer ring of the plurality of rings 12 is of lesser diameter in scope than those remaining. A plurality of short straps 14 are rigidly affixed to the outer ring and to the ring of nearest proximity thereto. These straps 14 serve the dual purpose of maintaining the two outer rings in spaced relationship, as well as providing a means for affording traction to cause the disintegrating unit to revolve as it is propelled over the earth by the implement to which it may be attached. The rings 12 nearest in relation to a propelling implement when ready for operation, are rigidly affixed in spaced relationship at alternate intervals, as shown in Figure 5. At other alternate intervals and on alternate rings, a means is provided for permitting certain portions of said rings to be capable of lateral movement in their mutual relationship, this movement, or vibration, tending to release sod from the roots of useless or undesirable vegetation. A pin 15, affixed at intervals to the rings 12, extends outwardly through elongated openings 16 through the straps 13, thereby permitting the lateral movement of said rings 12, as hereinbefore described.

Axial support of the disintegrating unit is accomplished by means of a collar 16a which fits circumferentially around an axle 17 of that portion of the invention used as a means for support of said unit and as a method of attachment to the propelling implement. Diagonally disposed spokes 18 affixed to the collar 16a, radiate outwardly to and are affixed to the outer ring of the disintegrating unit, thus providing a semi-rigid means for sustaining said unit in concentric relation to the axle 17. An additional collar 19 is made to encircle the end of the axle 17 to act as a means for maintaining the collar 16 in its proper operating position.

A similar collar 20 is slidably placed around the axle 17 and held in place by another collar 21, the latter having a set screw therein for rigid attachment to the axle 17, as is also the case with the collar 19 hereinbefore mentioned.

The axle 17 extends through a combination collar and clevis 22, having a collar 23 placed on each side of said clevis 22; these being similar in construction and means for attachment as in the case of the collars 19 and 21. A shaft 24 extends

transversely through the clevis 22 and is held in its desired position by means of a collar 25, similar in construction and design to the collars 19, 21 and 23 as hereinbefore described.

Attachment of the shaft 24 to the beam 10 of a plow is accomplished satisfactorily by means of a pair of opposing flat plates 26, which maintain a downwardly extending position of said shaft 24 in rigid juxtapositioned relationship with the side of said beam 10, the downwardly extending position of the shaft 24 in fairly rigid placement.

A short lug 28 is affixed subjacent the slidable collar 20, said lug 28 having a hole therethrough to receive a bolt 29 which is a means for joining said lug 28 with a flat extendable bar 30 extending angularly toward the beam 10 of a plow.

A pair of opposing flat plates 31 are held in place along the beam 10 by means of bolts 32, as illustrated in Figures 1 and 2. A link 33, extending from the side of the flat bar 30, encircles one of the bolts 32, thereby acting as a connector between the flat bar 30 and the beam 10, through fixed relationship with the plates 31. The angular position of the disintegrating unit in relation to the plow share 11 is obtained by longitudinal adjustment of the opposing plates 31 along the beam 10. Another means for such adjustment may be noted by reference to Figure 2, which illustrates in enlarged detail the plural membership of the flat bar 30. A plurality of holes 34 through said bar 30 is provided to receive bolts 35, thus providing means for shortening or lengthening the space defined between the extremities of said bar 30.

In operation, the invention is attached to an agricultural implement substantially as illustrated in Figure 1. The proximity of the disintegrating unit to the plow share 11, as shown, is governed by the depth of the furrow produced by the plow and the type of moldboard, if any, which may be in use, as well as the kind of soil being plowed. For best results the sod should strike within the disintegrating unit forward of the center of the axle 17 in order to tend toward producing a forward movement of said unit in order to eliminate as much drag as possible upon the implement to which it is attached. Other slight adjustments may be necessary in the case of excessive vegetation.

A modified form of the disintegrating unit is illustrated in Figures 3 and 4, in which said unit is designed and constructed as a tapering spiral having a series of convolutions 36 of circular cross-section. Certain ones of these convolutions are capable of movement in relation to adjacent

convolutions as hereinbefore described in reference to the rings illustrated in Figure 5. This relative movement tends to release the sod from the roots of vegetation by agitation in order that the roots may be more quickly disposed upon the freshly turned earth.

Axial support of this modification is obtained by lateral extensions of the spiral to a concentric collar 37 capable of circumferential placement upon the axle 17 as hereinbefore described in reference to the collar 16.

Manifestly, the construction as shown and described is capable of some modification and such modification as may be construed to fall within the scope and meaning of the appended claims is also considered to be within the spirit and intent of the invention.

What is claimed is:

1. A weed eradicating attachment for a plow comprising a sod disintegrating cage consisting of a plurality of rings of equal diameter and an outer ring of less diameter than the first mentioned rings, a series of lateral strips spaced circumferentially about said cage and connected stationarily with the two outer rings of said cage, means connecting the inner of said rings to said strips for limited lateral displacement with respect to one another and means for attaching said cage to said plow.

2. In a weed and grass eradicating attachment for a plow, a sod disintegrating unit comprising a plurality of relatively spaced rings sustained for free rotation by radially extending spokes from a centrally located hub within said unit, the most outwardly positioned ring being of lesser diameter than those remaining, stationary straps extending from said ring of lesser diameter to the nearest remaining ring to provide traction with the earth, and means for loosely connecting alternate portions of the rings to permit said rings to obtain movement in relation to the remaining rings.

DAVID R. JAMERSON.
